(57) CLAIM

The ornamental design for a handle, as shown and described.

DESCRIPTION

FIG. 1 is a top perspective view of a handle showing my new design;

FIG. 2 is a side view of the handle of FIG. 1; and,

FIG. 3 is a top view of the handle of FIG. 1.

A design for a handle is shown in FIGS. 1–3. The dash lines shown in the drawings are for illustrative purposes only and form no part of the claimed design.
